ELECTRON DISCHARGE DEVICE

William E. Shoupp, Wilkinsburg, Pa., assignor to
Westinghouse Electric Corporation, East Pitts-
burgh, Pa., a corporation of Pennsylvania

Application May 10, 1947, Serial No. 747,254

4 Claims. (Cl. 250—27.5)

1

This invention relates to electron discharge devices generally referred to as magnetrons, and more particularly to tuning means for the same.

Even though improved manufacturing processes have attained more accurate fabrication of magnetrons, the tolerances necessarily allowed, or other causes, introduce frequency differences in magnetrons, which are even more aggravated in connection with production of oscillations of extremely short wave length, especially where the wave length is measured by not more than one digit in centimeters. Tuning of the magnetron to an intended precise or narrow band frequency after the magnetron is entirely assembled, on test or in use, is highly desirable. It is likewise desirable to be able to tune a magnetron while in use, from one precise frequency to another. Attempts have been made heretofore to obtain tuning by mechanical means within the magnetron operated by external control.

The present invention relates to and has for its object the tuning of a magnetron by electronic means, and more definitely, tuning by injecting electrons into the capacitative elements of a magnetron thereby altering resonant frequency of the operating element or elements. According to my invention this may be done by placing a special or auxiliary cathode above the oscillating elements of the magnetron anode and putting a modulation voltage between said cathode and the magnetron anode. The electrons from the auxiliary cathode will be drawn toward the anode and will enter the oscillating cavities and, if the frequency is somewhat less than the Larmor frequency, the electrons will have small radial amplitude due to the very strong magnetic field applied for magnetron operation and will travel in tight helices the general directions of which are roughly straight paths. I propose using the presence of these electrons between the capacitative elements of the inherent resonant circuits to cause the desired change in resonant frequency of the magnetron due to alterations of the dielectric constant and thereby obtain a frequency shift or tuning.

In addition to the broad object of obtaining electronic tuning, the invention contemplates obtaining frequency shift in proportion to electron current and readily controlled modulation power supply therefor.

Other objects of the invention will appear to those skilled in the art to which it appertains, as the description proceeds, both by direct recitation thereof and by implication from the context.

Referring to the accompanying drawing in 55 substantially in accordance with prior art prac-

2

which like numerals of reference indicate similar parts throughout the several views:

Figure 1 is an axially longitudinal section of a magnetron showing my improved tuning means therein;

Figure 2 is a plan of the construction of Figure 1, but with the cover or end plate removed, as on line II—II of Figure 1;

Figure 3 is an enlarged detail section of a portion of the auxiliary or tuning cathode at one electron emitting area and showing an associated portion of the anode, as on line III—III of Figure 5;

Figure 4 is a detail sectional view of a portion 15 of the anode on the same scale as Figure 3 taken on line IV—IV of Figure 3; and

Figure 5 is an underneath view of the auxiliary cathode showing the several emitting areas thereof.

20 In the specific embodiment of the invention illustrated in the several figures of the drawing, the reference numeral 10 designates a cylindrical metallic magnetron body, the ends whereof have cover or end plates 11 sealed thereon that the interior may be evacuated. Within and as an integral part of said body is the usual magnetron anode structure 12 of generally cylindrical shape but shorter than the outer part of the body so as to provide end spaces 13 between the anode and said end plates 11. The anode structure is axially hollow to provide a cathode cavity and radiating from this cathode cavity are a plurality of cavities 14 constituting cavity resonators each having, in the form shown, a cylindrical portion parallel to the cathode cavity and each cylindrical portion 25 having a longitudinal constricted capacitative slot 15 constituting a lateral opening from the cylindrical portion of the cavity into the hollow central part of cathode chamber of the magnetron. Said slots 15 extend the full length of the anode body so as to be open at their ends into said end spaces 13. The ends of the cathode cavity and the ends of said resonant cavities likewise open into the end spaces 13.

45 An indirectly heated cathode 16 passes axially through the cathode cavity, adequately spaced from the anode and supported as usual from lead-in rods 17 entering the end cavities at the sides thereof. An output loop 18 is situated in one of the resonant cavities 14, passing out through the side wall of the body 10 in accordance with usual practice. The size and shape of the magnetron body, the end spaces, anode, cathode and leads above described are preferably all 50 substantially in accordance with prior art prac-

tice, in consequence of which the pole pieces of the magnet, not shown, will have the same relation to the magnetron and its anode as exists in magnetrons as heretofore used.

In carrying out the present invention an auxiliary cathode 19, of generally ring or doughnut shape, is shown concentrically situated in one of said end spaces 13, and in this instance is located in the upper one of said spaces. The said auxiliary cathode occupies a position overlying the upper ends of the anode slots 15 and preferably has a radial width substantially equal to the radial length of said slots. Thus, while the auxiliary cathode overlies those portions of the anode intervening between the slots, it does not overlie other portions of the anode nor does it overlie the generally cylindrical portion of the cavities constituting the cavity resonators.

Said auxiliary cathode is shown as a casting comprising a substantially flat, washer-like under wall 20 and a flanged toroidal upper wall 21, the flanges 22 of which are secured to the upper flat marginal surfaces of the under wall. The toroidal wall is split radially at one part thereof so as to provide separated ends 23 therefore which face toward each other. Coaxially within said toroidal wall 21 and spaced above the flat under wall 20 is a heater 24, here shown as a single-strand resistance wire, the ends of which protrude from the two said ends 23 of the torus. One of said ends of the heater 24 is connected to the auxiliary cathode casing and the other end of said heater is connected to a lead-in rod or wire 25 the inner end of which is shown protruding radially of the magnetron end space 13 to a location between and out of contact with said ends 23 of the torus and out of contact with said under wall 20. The interior of the torus or auxiliary cathode casing contains a suitable electrical insulation material 26 for maintaining desired electrical isolation of the heater, except where attached at its one end, from said casing of the auxiliary cathode.

Support for and electrical connection to the auxiliary cathode casing is obtained by another radially disposed lead-in rod or wire 27. For that purpose a partial sleeve 28 is shown integral with and projecting radially from said torus and this sleeve is in turn soldered or otherwise secured on the end portion of the lead-in rod or wire 27. This lead-in rod 27 constitutes electrical connection both for the auxiliary cathode and for one end of the heater. The other or first-mentioned lead-in rod 25 connects only with the other end of the heater so as to obtain a complete heater circuit to the exterior. Insulative mounting and passage of both lead-in wires is alike and accords with prior art practice for lead-in wires as to construction, so requires no elaboration herein.

On the under face of the flat under wall 20 of the auxiliary cathode, at the areas directly overlying the upper ends of the slots 15 of the anode, are electron emissive patches 29. These patches may be of any appropriate material for copious emission of electrons, of which alkaline earths, such as barium and strontium or their oxides, are examples. By virtue of the focusing of the magnetic field and the fact that the restricted emissive areas or patches are directly over the slots of the anode, emission is beamed into said slots with negligible spreading of the beam or scattering of the electrons. The electrons will be collected at the far end of anode block. The parallel walls forming the slots con-

stitute the capacitative elements and said slots are the regions of highest capacity of the self-contained resonant circuit within the device. Presence in and passage through said slots of electrons, alters the capacitance thereof and thus the capacitative element of the circuit is directly effected and the frequency shift will be proportional to the electron current, and can be controlled externally by the modulation power supply to the auxiliary cathode. Attention is called to the fact that while electrons are emitted from the main cathode 16 in a direction radially of the anode body, the electrons from the auxiliary cathode 19 are emitted in an axial direction of the anode body.

Frequency modulation is, therefore, in consequence of the structure described above, produced electronically by means of a separate modulation power supply used in conjunction with the auxiliary cathode, and without need for any moving mechanical parts in the magnetron.

I claim:

1. A magnetron having an anode providing a cathode cavity and a series of cavity resonators radiating therefrom and having end spaces at opposite ends of said anode, said resonators having substantially parallel capacitative elements radiating from and next the parts thereof toward said cathode cavity, a main cathode in said cathode cavity, and an auxiliary ring-shaped cathode in one of said end spaces coaxial with said cathode cavity and overlying said anode only to extend from the said cathode cavity to substantially the most distant part therefrom of said parallel capacitative elements, the ends of the resonators being otherwise open to said end spaces.

2. A magnetron having an anode providing a cathode cavity and a circular series of evenly spaced cavity resonators radiating therefrom and having end spaces at opposite ends of said anode, said resonators having capacitative elements next the parts thereof toward said cathode cavity, a main cathode in said cathode cavity, and an auxiliary ring-shaped cathode in one of said end spaces coaxial with said cathode cavity and overlying said anode only to an extent from the said cathode cavity to substantially the most distant part therefrom of said capacitative elements, the ends of the resonators being otherwise open to said end spaces, and said auxiliary cathode having a plurality of equally spaced electron emissive patches equal in number to the number of cavity resonators in said series.

3. A magnetron having an anode providing a cathode cavity and a circular series of evenly spaced cavity resonators radiating therefrom and having end spaces at opposite ends of said anode, said resonators having capacitative elements next the parts thereof toward said cathode cavity, a main cathode in said cathode cavity, and an auxiliary ring-shaped cathode in one of said end spaces coaxial with said cathode cavity and overlying said anode only to an extent from the said cathode cavity to substantially the most distant part therefrom of said capacitative elements, the ends of the resonators being otherwise open to said end spaces, and said auxiliary cathode having a plurality of equally spaced electron emissive patches equal in number to the number of cavity resonators in said series, said patches each directly overlying a pair of said capacitative elements.

4. A magnetron having an anode providing a cathode cavity and a circular series of evenly spaced cavity resonators, each of said resonators

having a slot radiating from said cathode cavity with substantially flat parallel faces defining the full radial depth of said slot and having a cylindrical portion at the outer end of the slot, said anode providing intervening wall portions between successive slots of the series of resonators, a main cathode within said cathode cavity, and an auxiliary cathode overlying only said wall portions and slots so as to direct electron flow into said slots throughout the entire radial depth of said slots substantially in a general path parallel to the main cathode.
